CLAIM

The ornamental design for a pendant, as shown.

DESCRIPTION

FIG. 1 is a front elevational view of a pendant, showing my new design.

FIG. 2 is a plan view of the top face of the pendant. The plan view of the bottom face of the pendant, not shown, is symmetrical.

FIG. 3 is a view of the pendant as would appear from the left side of FIG. 2.

FIG. 4 is a view of the pendant as would appear from the right side of FIG. 2.

FIG. 5 is a view of the pendant as would appear from the top end of FIG. 2; and,

FIG. 6 is a view of the pendant as would appear from the bottom end of FIG. 2.
